UNITED STATES PATENT OFFICE.

HENRY MUELLER, OF DECATUR, ILLINOIS, ASSIGNOR TO H. MUELLER MANUFACTURING COMPANY, OF DECATUR, ILLINOIS.

INDEX FOR COCKS.

No. 857,957.

Specification of Letters Patent.

Patented June 25, 1907.

Application filed July 30, 1906. Serial No. 328,478.

To all whom it may concern:

Be it known that I, HENRY MUELLER, of the city of Decatur, county of Macon, and State of Illinois, have invented certain new and useful Improvements in Indexes for Cocks and the Like, of which the following is a specification.

This invention relates to cocks adapted for use with hot water or cold water, or with other liquids of different kinds, and the object is to provide for indicating either of a plurality of uses for which the cock may be adapted.

The invention is embodied in a rotatable index member normally held against rotation between two clamping surfaces, formed in or on the cock, and provided with different words or signs at different places around its perimeter. The mode of operation is to loosen clamping pressure on the index member, to rotate the index member until the word or sign descriptive or suggestive of the desired use of the cock is presented in proper position for ready observation, and to then re-tighten the clamp.

The invention is exemplified in the structure hereinafter described, and it is defined in the appended claims.

In the drawings forming part of this specification, Figure 1 is a front elevation of a right-and-left basin cock of the "Fuller" type, said cock being provided with an index member constructed and secured in accordance with my invention. Fig. 2 is a side elevation of the cock shown in Fig. 1, with the index member and adjuncts thereof in central vertical section. Fig. 3 is a detail in elevation of the index member for the cock body. Fig. 4 is a detail in plan of the index member.

The fixed body of the cock is shown at 1 and at 2 is shown a concaved seat therein for the support of the index member 5, which is commonly called a button, and is of convexo-convex form, in this instance. The seat 2 is bored and threaded, the button is bored centrally, as shown at 6 in Fig. 4, and a screw 10 is inserted through the button and screwed into the central seat until the button is clamped in place between the seat 2 and the head 3 of the screw.

The button has different words or indicating signs on opposite sides of its circumference, which project beyond the seat 2 and

the head 3, the words "hot" and "cold" 55 being used in this instance, and either word may be placed in position to confront those using the cock. When the cock is used for hot water the word "hot" is presented to the front, or placed in position to be readily seen, 60 and when the cock is used for the cold water the position of the button is reversed. If the cock had other uses and the button were provided with words or signs indicating such uses, the operation would obviously be the 65 same.

The advantage of the reversible, shiftable, or variable index is obviously to enable a single cock to be used intelligently for a plurality of purposes; thus obviating the necessity for carrying in stock a selection of special cocks for each separate use. 70

The invention is particularly applicable to right-and-left cocks, or to cocks which are neither right nor left, as cross-handle compression cocks for instance, but it has some utility in connection with any kind of a cock and I do not restrict its use to any special form of cock. 75

I claim,—

1. The combination of a fixed cock body having a button seat in its upper end, said seat being centrally bored and screw-threaded, a centrally-bored index button adapted to rest on the seat of the cock and to be rotatably adjusted thereon, said button having different indications on its different sides, and a screw adapted to screw into the cock through the bore of the button and clamp the button in place, substantially as described. 80 85

2. The combination with a cock having a concave button seat bored and threaded, and a screw whose tip is adapted to engage said threaded bore; of a convexo-convex button of greater diameter than the seat or the head 95 of the screw and whose projecting face has different indications on its different sides, said button being bored for the passage of the shank of the screw and clamped between said head and seat with the proper indication 100 confronting the user, substantially as described.

In testimony whereof I sign my name in the presence of two subscribing witnesses.

HENRY MUELLER.
